(57) **CLAIM**

The ornamental design for a universal button module, as shown and described.

DESCRIPTION

This application is also related to co-pending U.S. Design patent application Ser. Nos. 29/276,739, 29/276,740, 29/276,741, 29/276,742, 29/276,745, 29/276,746, 29/276,747, 29/276,748, 29/276,749, 29/276,750, 29/276,751, concurrently filed on Feb. 2, 2007, and also entitled “Universal Button Module”.

FIG. 1 is a perspective view of a universal button module showing our new design;

FIG. 2 is a top planar view of the universal button module shown in FIG. 1;

FIG. 3 is a front elevational view of the universal button module shown in FIG. 1;

FIG. 4 is a left side elevational view of the universal button module shown in FIG. 1;

FIG. 5 is a right side elevational view of the universal button module shown in FIG. 1;

FIG. 6 is a perspective view of an alternate embodiment of the design shown in FIG. 1;

FIG. 7 is a front perspective view of a universal button module showing our new design;

FIG. 8 is a top planar view of the universal button module shown in FIG. 7;

FIG. 9 is a front elevational view of the universal button module shown in FIG. 7;

FIG. 10 is a left side elevational view of the universal button module shown in FIG. 7;

FIG. 11 is a right side elevational view of the universal button module shown in FIG. 7; and,

FIG. 12 is a perspective view of an alternate embodiment of the design shown in FIG. 7.

The broken lines showing a button display in FIGS. 1 and 2, and the broken lines showing a partial gaming device in FIGS. 6 and 12 are for illustrative purposes only and form no part of the claimed design.
